(57) **CLAIM**

The ornamental design for an integrated aquarium and small animal exhibit, as shown and described.

DESCRIPTION

FIG. 1 is a perspective view of an integrated aquarium and small animal exhibit showing my design;

FIG. 2 is a front view of FIG. 1; and,

FIG. 3 is a front view of FIG. 1 showing the cabinet's access door open to reveal the small animal enclosure contained therein.

Portions of the integrated aquarium and small animal exhibit shown in broken lines form no part of the claimed design.

1 Claim, 3 Drawing Sheets

FIG. 1

FIG. 2***FIG. 3***
